UNITED STATES PATENT AND TRADEMARK OFFICE
CERTIFICATE OF CORRECTION

PATENT NO. : D707,105 S
APPLICATION NO. : 29/396279
DATED : June 17, 2014
INVENTOR(S) : Bruce W. Irving

Page 1 of 1

It is certified that error appears in the above-identified patent and that said Letters Patent is hereby corrected as shown below:

Title page, item 57

In the claim, delete "The ornamental design for a H style divider matrix sleeve, as shown and described." and replace with --The ornamental design for a Clear Plastic Lateral HDM (H Style Divider Matrix) Sleeve as shown and described.--

Signed and Sealed this
Eleventh Day of November, 2014

Michelle K. Lee
Deputy Director of the United States Patent and Trademark Office
